PETER GYSBERT THOMAS DE VILLIERS, OF PRETORIA, TRANSVAAL, SOUTH AFRICA,
ASSIGNOR OF ONE-HALF TO ARTHUR ROGERS-JENKINS, OF DURBAN, NATAL,
UNION OF SOUTH AFRICA.

SLOT LOCK FOR COIN-COLLECTING BOXES.

Application filed December 3, 1920. Serial No. 427,952.

To all whom it may concern:

Be it known that PETER GYSBERT THOMAS DE VILLIERS, a British subject, residing at Department of Posts and Telegraphs, general 5 post office, Pretoria, Transvaal Province of the Union of South Africa, has invented certain new and useful Improvements in Slot Locks for Coin-Collecting Boxes, of which the following is a specification.

10 The present invention relates to coin collecting boxes, more especially removable boxes for coin-in-the slot machines.

The purpose of the invention is to provide for the box being automatically locked after 15 use, so that the contents cannot be tampered with.

In the accompanying drawings,

Fig. I shows a coin collecting box with part of its housing.

20 Fig. II is a vertical section through Fig. I, showing the box fully in its housing.

Fig. III shows the inside of the box lid with the lock device in the set position.

Fig. IV shows the lock device when the 25 box is in the housing.

Fig. V is a similar view to Fig. IV showing the lock device in the position which it assumes after the box has been inserted into and subsequently withdrawn from the ma- 30 chine.

The collecting box 1 is provided with a coin receiving slot 2, and the ordinary lock 3, which is intended to be operated only by some authorized person other than the box 35 collector.

Inserted within the lid of the box and removably held therein by clips 4 is a base plate 5 having an aperture 6 which registers with the coin receiving slot 2 in the lid. A 40 slot closing tongue 7 is pivoted to the base plate 5 at 8 so that it may cover the slot 2 as indicated in Figs. I, III and IV or be thrust aside to disclose said slot, as shown in Figs. II and IV. A guide 9 is provided 45 for supporting the outer end of said tongue 7 in close contact with the aperture 6 and said tongue tends to be moved to the closed position by means of a spring 10 mounted on the pivot 8 and pressing on a pin 11 pro- 50 jecting from the tongue 7.

A ward 12 is pivoted at 13 and is urged to the left of Fig. III by a continuation 14 of the spring 9, which engages a lug 15 on it. In said ward is formed a slot 16, 17, 18

through which the pin 11 projects. Said 55 slot is roughly of V shape, so that as the tongue 7 is moved to uncover the slot 2 the pin 11 moves up the leg 16 of the slot, and when it reaches the top of the same the ward is moved by the spring 14 partly over to the 60 left to bring the pin into the leg 17 of the slot, Fig. IV. When the tongue 7 is allowed to move back over the slot 2, the pin 11 accordingly moves down the leg 17 of the slot. Said leg 17 terminates in an extension slot 65 18 which is substantially circumferential with regard to the pivot 13; and upon the pin 11 reaching the lower end of the leg 17, the spring 14 pushes over the ward 12 so as to bring said pin 11 into the extension slot 70 18. The tongue 7 is thereby definitely locked against movement until the box is opened and the ward 12 is manipulated against its spring 14 to release the pin 11 from the extension slot 18.

In the construction shown the tongue 7 is moved to uncover the aperture 6 and thereby also bring the pin 11 into the leg 17 of the slot by the operation of inserting the box into its housing 19. For this purpose the 80 tongue 7 is formed with a downwardly extended lug 20 and on the inside of the housing 19 there is fixed a pin 21. As the box is slid into the housing, said pin 21 passes through a small aperture 22 in the rear wall 85 of the box, and thrusts the tongue 7 over to open the aperture 6.

The leg 17 of the slot is longer than the leg 16 thereof, so that when the tongue 7 returns after having been thrust back by the 90 pin 21, it occupies a different position relatively to the slot 2, from its initial position when set. In its initial position it exposes through the slot 2 the word "Set," but the further movement due to its re-closing, 95 causes said word "Set" to pass beyond the slot and to be obscured, thus indicating that the box has been inserted into the machine, and should therefore be delivered for collection of its contents.

In use the tongue 7 is set in the position indicated in Fig. III, the box is locked in the ordinary way and given to the collector; the word "Set," which is exhibited through the slot 2, indicating that it is an empty box 105 ready to be inserted into the machine. The collector then simply pushes it into its housing 19, and that operation moves the

tongue 7 to open the slot 2 for the reception of coins. In due course the box is removed from the machine, which operation restores the tongue 7 to position over the slot 2 and 5 also locks the same to secure the contents of the box. The disappearance of the word "Set" indicates that the box should now be taken back to the proper authority for removal of its contents, and re-setting of the 10 lock device.

I claim:

1. The combination with a coin collecting box having a coin receiving slot, of a housing for said box, a closure for said slot adapted 15 to be opened by insertion of the box into its housing and to close upon its removal from said housing, and means dependent upon opening and closing movement of the closure to lock the same.
2. The combination with a coin collecting box having a coin receiving slot, of a housing therefor, a closure tongue for the slot adapted to be displaced from the slot to open the same by contact with a fixed part of the 25 housing, a spring tending constantly to close the tongue, and means actuated upon open-

ing and closing movement of the tongue to lock the same.

3. The combination with a coin collecting box having a coin receiving slot, of a spring 30 actuated tongue tending to close said slot and being displaceable therefrom, a ward having spring means tending to move it in a definite direction, a pin and slot connection between the tongue and the ward providing 35 a pin path which, in an opening and subsequent closing movement of the tongue, provides a component in the direction in which the ward is actuated by its spring and providing a further path element in which the ward locks the tongue.

4. The combination with a coin collecting box having a coin receiving slot, a closure movable to open and close said slot, a spring tending to move said closure to the slot 40 covering position, and means actuated upon the closure being opened and then closed, to cause the closure to assume a final position different from its initial position.

In testimony whereof I affix my signature. 50

PETER GYSBERT THOMAS de VILLIERS.
